(57) **CLAIM**

The ornamental design for a Under Water Communication Device as shown and described.

DESCRIPTION

FIG. 1 is a perspective view of a first embodiment of a Under Water Communication Device showing my new design;

FIG. 2 is another perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and

FIG. 8 is a bottom plan view thereof.

FIG. 9 is a perspective view of a second embodiment of the Under Water Communication Device showing my new design;

FIG. 10 is another perspective view thereof;

FIG. 11 is a right side elevational view thereof;

FIG. 12 is a left side elevational view thereof;

FIG. 13 is a front elevational view thereof;

FIG. 14 is a rear elevational view thereof;

FIG. 15 is a top plan view thereof; and

FIG. 16 is a bottom plan view thereof.

The broken lines in the drawings depict portions of the Under Water Communication Device that form no part of the claimed design.

1 Claim, 16 Drawing Sheets
